(57) **CLAIM**

The ornamental design for a sponge handle, as shown and described.

DESCRIPTION

FIG. 1 is a perspective view of a sponge handle showing my invention;

FIG. 2 is a back side view thereof;

FIG. 3 is a top side view thereof, the bottom side being a mirror image thereof; and,

FIG. 4 is a right side view thereof, the left side being a mirror image thereof.

The broken lines of the hole and the sponge head section are for illustrative purposes only and form no part of the claimed design.
